C. W. VOGT
COMBINATION HOPPER AND FUEL FEEDING AND
DISTRIBUTING CONSTRUCTION FOR FURNACES
Filed Jan. 26, 1923

UNITED STATES PATENT OFFICE.

CLARENCE W. VOGT, OF LOUISVILLE, KENTUCKY, ASSIGNOR TO VOGT BROTHERS MFG. CO., OF LOUISVILLE, KENTUCKY, A CORPORATION.

COMBINATION HOPPER AND FUEL-FEEDING AND DISTRIBUTING CONSTRUCTION FOR FURNACES.

Application filed January 26, 1923. Serial No. 615,112.

To all whom it may concern:

Be it known that I, CLARENCE W. VOGT, a citizen of the United States, and a resident of Louisville, county of Jefferson, 5 and State of Kentucky, have invented a certain new and useful Combination Hopper and Fuel-Feeding and Distributing Construction for Furnaces; and I do hereby declare that the following is a full, 10 clear, and exact description thereof, reference being had to the accompanying drawings, in which like numerals refer to like parts.

This invention relates to a combination 15 hopper and fuel feeding and distributing construction for furnaces, boilers and the like.

The chief object of this invention is to construct a construction of the character 20 indicated in such a manner that hand stoking is possible and the resultant fuel distribution is of uniform character.

The chief feature of the invention, in addition to the accomplishment of the foregoing objects, is a furnace opening provided 25 with a plurality of fan-tail shaped spreader plates with which are associated a plurality of hopper supported aligned and seated rams, each being in alignment with 30 one of the spreader plates.

The full nature of the invention will be understood from the accompanying drawings and the following description and claims.

35 In the drawings, Fig. 1 is a longitudinal sectional view of a furnace showing a portion of a grate and the hopper associated therewith. Fig. 2 is a rear perspective view of the hopper including the spreader plates. Fig. 3 is a front perspective view of the hopper including 40 the spreader plates and actuating mechanisms.

In the drawings 10 indicates a furnace 45 construction having a grate 11 and a single mouth 12. Positioned in the mouth 12 is a plurality of corrugated coking plates 13 each having a supporting bracket portion 14 adapted to support said plate in inclined position so as to discharge the fuel received thereby on to the adjacent inclined grate 11.

The hopper consists of a pair of end plates 15 substantially triangular in shape

and positioned at each side of the mouth 55 12, and connecting said end plates is a hinge rod 16 which supports a hingedly mounted back plate 17. The hingedly mounted back plate 17 terminates short of the hopper bottom 18 which closes the 60 lower end of the hopper. The bottom 18 is provided with a plurality of depressions 19. The upper end of a fan-shaped spreader plate 20, having a corrugated surface is 65 suitably secured in alignment with each of said depressions. The spreader plates 20 discharge upon a corrugated coking plate 13. Slidably supported in each depression 19 is a ram 21 having a lower and pushing 70 face 22 and a rack-toothed under face 23. 70

The hingedly supported back plate 17 permits the rams to be slidably supported between the bottom 18 and the same. Each depressed portion 19 is apertured as at 24, and positioned upon opposite sides of the 75 slot or opening 24 is a rearwardly extending bracket 25 which forms a support or ear for a pivot 26 upon which is pivotally mounted a sector gear or gear segment 27. A handle 28 is associated therewith for 80 tilting the gear segment upon its pivot. The teeth of the gear segment extend through aperture 24 and mesh with the rack teeth 23 upon the back of the ram 21. In this manner, movement of the handle 85 from the position shown in Fig. 1, counter-clockwise, to a lower position, serves to withdraw the ram from the mouth 12 of the furnace into the space between the back plate 17 and the bottom plate 19. Thereafter a clockwise or upward return movement of the handle 28 serves to move the ram from its upper and retracted position 90 into its lower or forward position. In this movement, the ram forces the coal or other solid fuel on to the spreader plates 20, and from thence fuel passes on to the coking plate 13 to be subsequently discharged upon 95 the grate, where it is completely burned. As shown clearly in Figs. 1 and 2, the ram 100 above the forward face 22 and along the edge thereof is provided with a plurality of teeth 29 which assist in the movement of the coal when it is being fed into the furnace and permit the ready retraction of 105 the ram in the retractile movement thereof.

Suitable lugs 30 and 31 positioned respectively upon the bottom 18 and the ends 15

provide retaining means for holding the rams in place upon the bottom plate 19. The spreader plate is suitably connected to the bottom by means of the bolts 32. The intermediate lugs 33 and end flanges 34 are adapted to rigidly secure the hopper in position adjacent the furnace 10 and in juxtaposition to the furnace mouth 12.

- 5 The invention claimed is:
- 10 1. In a furnace having an opening, the combination of a hopper extending upwardly and outwardly therefrom, a plurality of rams arranged in spaced and parallel relation and slidably supported therein for discharging fuel into said opening, and a plu-
  - 15

rality of divergingly corrugated spreading plates each in line with a ram for receiving fuel therefrom and distributing the same in a body substantially the full width of the opening in width.

20 2. A device of the character described in claim 1 characterized by the hopper having suitable recesses therein for receiving said rams and a hinged plate having its free edge bearable on the hopper bottom and clearing said rams.

25 In witness whereof, I have hereunto affixed my signature.

CLARENCE W. VOGT.
